UNITED STATES PATENT OFFICE.

PHILEMON O. DICKINSON, OF NEWARK, NEW JERSEY, ASSIGNOR TO UNGER BROTHERS, OF SAME PLACE.

DESIGN FOR A BACK FOR BRUSHES, &c.

SPECIFICATION forming part of Design No. 26,272, dated November 17, 1896.

Application filed October 10, 1896. Serial No. 608,526. Term of patent 3½ years.

To all whom it may concern:

Be it known that I, PHILEMON O. DICKINSON, a citizen of the United States, residing at Newark, in the county of Essex and State 5 of New Jersey, have invented and produced a new and original Design for Backs of Brushes, of which the following is a description, reference being had to the drawing accompanying and forming a part of the same.

10 The general outline of the back is rectangular, but having the rounded corners A B and ends C.

The entire surface of the upper and lower portions of the brush are covered by masses 15 of shell, scroll, foliate, and flower figures, arranged after the rococo order. Thus D is a scalloped shell, E a pearly and scrolled shield, and F represents leaves, while G shows flowers, the intermediate portions between

which are filled with various forms of scroll 20 and shell-like figures. At the middle of the brush is the plain surface H, bounded, essentially, by the shell border I, and the beaded scroll J, the shell and shield D and E being reversed as to their relative location at the upper end of the handle from their arrangement 25 as shown at the lower end of the handle.

The essential features of the design are those above set forth.

What is claimed as new is—
30 The design for backs of brushes and similar articles, substantially as shown and described.

PHILEMON O. DICKINSON.
